UNITED STATES PATENT OFFICE.

CLARENCE E. MULLENS, OF ALBANY, NEW YORK.

BONE CLAMP.

Application filed January 11, 1927. Serial No. 160,438.

The present invention is concerned with the provision of a surgical instrument primarily intended for use in setting broken bones, such for instance as arm or leg 5 bones.

An object of the invention is to provide an instrument with which the two sections of a broken bone may be accurately aligned and held in properly aligned position until 10 such time as the plaster cast ordinarily used becomes hardened.

Bone clamps as heretofore used have consisted of two separate clamping elements. The surgeon having made an incision to expose 15 the two sections of bone at the break, holds a clamp in each hand, and grasping with them the two sections of bone, endeavors to properly align the sections.

This method is particularly satisfactory 20 due primarily to the fact that much depends upon the skill of the surgeon and the steadiness with which he is able to hold the bone clamps.

In accordance with the present invention, 25 both clamps are made a part of one instrument. They are individually adjustable to engage the two sections of bone to be aligned, but means is provided for securely locking the two clamps against any relative movement 30 after they have been applied.

Other objects of the invention are to provide a surgical instrument of the character above noted which will be of extremely simple practical construction, rugged, durable and efficient in use, easy to manipulate, and well suited to the requirements of economical manufacture.

With the above noted and other objects in view, the invention consists in certain novel 40 features of constructions and combinations and arrangements of parts, as will be more fully hereinafter set forth and pointed out in the claims. The invention may be more fully understood from the following description 45 in connection with the accompanying drawings, wherein—

Fig. 1 is a perspective view of a bone clamp embodying the present invention.

Fig. 2 is a top plan view thereof with a 50 section of the block broken away to expose the trunnion on which one of the clamp arms is rockably adjusted.

Fig. 3 is a view in side elevation of the 55 bone clamp showing the jaws separated, the dotted lines indicating the position of the jaws when closed.

Fig. 4 is a fragmentary longitudinal sectional view showing the mechanism for locking the movable jaws in adjusted position.

Fig. 5 is a side elevation of the block and 60 stationary jaws with the adjustable jaws removed.

Fig. 6 is a view in side elevation of one of the adjustable jaws.

I have used the reference character 10 to 65 designate a body or block from the forward edge of which project a pair of integral arms 11 supporting lower stationary jaw members 12. The jaw members 12 are adapted for coaction with upper movable jaws 13 carried 70 by arms 14. These arms are integral with sector plates 15 lying on opposite sides of the block 10 and pivoting on trunnions 15^a pocketed in the outer faces of the block. The sector plates at their larger ends are formed 75 with arcuate slots 16 receiving respectively the head 17 of a bolt 18 passed transversely through the block 10 and a nut 19 screwed on to the threaded end 20 of the bolt. The walls of the slots 16 are shouldered as at 21 providing shoulders or lips which may be engaged by the head 17 and nut 19 respectively when the nut is tightened. It will thus be apparent that by tightening the nut, the sector plates 15 are clamped firmly against the 80 sides of the block and the movable jaws 13 locked against movement. To render this engagement still more firm, the outer faces of the block and the inner faces of the sector plates are provided with cooperating 85 toothed or otherwise roughened portions 22 which assure firm frictional engagement.

To facilitate the manipulation of the movable jaws 13, each of the sector plates 15 may be provided with a movable handle 23, while 90 an additional handle 24 may be attached to the block 10.

The manner of use of the tool is substantially as follows. The surgeon first makes an incision to expose the broken ends of the 100 two bone sections which are being aligned and set. Through this incision he inserts the clamps 12, 13, and individually manipulates the handles 23 until the two sections of bone have been engaged and aligned by the respective clamps. The individual adjustment of the jaws 13 is desirable due to the fact that one section of bone may be larger than the other. Having thus aligned the two bone sections, the two sets of jaws 110 12, 13 are securely locked against relative movement or individual movement by the

simple expedient of tightening the bolt 18. This tightening action may be conveniently accomplished by the use of a wrench shown in dotted lines at 25 (Fig. 4) which is inserted into a square socket 26 in the bolt head 17. Having tightened the bolt to lock the jaws against movement, the jaws are concealed within a protective covering of any kind. This covering may for instance 10 comprise a box (not shown). The plaster is then applied over a comparatively large area, but the box or other protective device prevents it from coming in contact with the incision.

15 This protecting device is also so constructed that the bone clamp may be removed after the plaster has set. After the cast has set therefore, the physician unlocks the bolt 18, releases the jaws 12, 13 from their clamping engagement with the aligned bone sections, removes the tool and closes the incision.

20 Obviously, various changes and alterations might be made in the general form and arrangement of parts described without departing from the invention. Hence I do not wish to limit myself to the details set forth, but shall consider myself at liberty to make such changes and alterations as fairly fall 25 within the spirit and scope of the appended claims.

I claim:

1. A bone clamp including a body, a pair 35 of spaced stationary jaws rigidly connected to said body, a pair of spaced movable jaws movably connected to said body and cooperating with the stationary jaws, means for independently adjusting the movable jaws, and means for locking said jaws in any desired 40 position of relative adjustment.

2. A bone clamp including a body, a pair 45 of spaced stationary jaws rigidly connected to said body, a pair of spaced movable jaws movably connected to said body and cooperating 50 with the stationary jaws, means for independently adjusting the movable jaws, and means for locking said jaws in any desired position of relative adjustment, said body comprising a block and the stationary jaws being rigid with curved arms projecting 55 from the block.

3. A bone clamp including a body, a pair 55 of spaced stationary jaws rigidly connected to said body, a pair of spaced movable jaws movably connected to said body and cooperating 60 with the stationary jaws, means for independently adjusting the movable jaws and means for locking said jaws in any desired position of relative adjustment, said body comprising a block, the movable jaws being carried by arms pivoted intermediate their ends to the outer faces of opposite sides of 65 the block.

4. A bone clamp including a body, a pair 65 of spaced stationary jaws rigidly connected

to said body, a pair of spaced movable jaws movably connected to said body and cooperating with the stationary jaws, means for independently adjusting the movable jaws and means for locking said jaws in any desired 70 position of relative adjustment, said body comprising a block, the movable jaws being carried by arms pivoted intermediate their ends to the outer faces of opposite sides of the block, the arms including enlarged sector 75 shaped portions having arcuate slots therein and a clamping bolt passed through the block and having its ends disposed in the slots.

5. A bone clamp including a body, a pair 80 of spaced stationary jaws rigidly connected to said body, a pair of spaced movable jaws movably connected to said body and cooperating with the stationary jaws, means for independently adjusting the movable jaws and means for locking said jaws in any desired 85 position of relative adjustment, said body comprising a block, the movable jaws being carried by arms pivoted intermediate their ends to the outer faces of opposite sides of the block, the arms including enlarged sector 90 shaped portions having arcuate slots therein and a clamping bolt passed through the block and having its ends disposed in the slots, said slots being shouldered for engagement 95 with the ends of the clamping bolt to lock the arms against pivotal movement.

6. A bone clamp including a body, a pair 100 of spaced stationary jaws rigidly connected to said body, a pair of spaced movable jaws movably connected to said body and cooperating with the stationary jaws, means for independently adjusting the movable jaws and means for locking said jaws in any desired position of relative adjustment, said body comprising a block, the movable jaws being carried by arms pivoted intermediate their ends to the outer faces of opposite sides of the block, the arms including enlarged sector 105 shaped portions having arcuate slots therein and a clamping bolt passed through the block and having its ends disposed in the slots, said slots being shouldered for engagement with the ends of the clamping bolt to lock the arms against pivotal movement, and means for tightening the bolt to clamp the arms.

7. A bone clamp including a body, a pair 110 of spaced stationary jaws rigidly connected to said body, a pair of spaced movable jaws movably connected to said body and cooperating with the stationary jaws, means for independently adjusting the movable jaws and means for locking said jaws in any desired 115 position of relative adjustment, said body comprising a block, the movable jaws being carried by arms pivoted intermediate their ends to the outer faces of opposite sides of the block, the arms including enlarged sector 120 shaped portions having arcuate slots therein and a clamping bolt passed through the block and having its ends disposed in the slots, said slots being shouldered for engagement with the ends of the clamping bolt to lock the arms against pivotal movement, and means for tightening the bolt to clamp the arms.

125

the block and having its ends disposed in the slots, said slots being shouldered for engagement with the ends of the clamping bolt to lock the arms against pivotal movement, 5 the over-riding faces of the sector plates and blocks being toothed to prevent slippage when the bolt is tightened.

8. A bone clamp comprising a block, a pair of substantially parallel arms projecting from one end of the block and rigid therewith, jaws at the ends of the arms, a second pair of arms pivotally connected to opposite sides of the block and including jaw portions coacting with the first mentioned jaws, and means for adjusting the pivoted arms and for selectively locking them in adjusted position.

10. A bone clamp including a pair of substantially parallel rigidly connected arms including jaw portions, a movable arm associated with each of the first mentioned arms and each including a jaw coacting with the first mentioned jaws, means for adjusting the movable arms and for selectively locking them in any position of adjustment.

15. A bone clamp comprising a block, a pair of substantially parallel arms project-

ing from one end of the block and rigid therewith, jaws at the ends of the arms, a second pair of arms pivotally connected to opposite sides of the block and including jaw portions coacting with the first mentioned jaws, and means for adjusting the pivoted arms and for selectively locking them in adjusted position.

20. A bone clamp including a pair of substantially parallel rigidly connected arms including jaw portions, a movable arm associated with each of the first mentioned arms and each including a jaw coacting with the first mentioned jaws, means for adjusting the movable arms and for selectively locking them in any position of adjustment.

CLARENCE E. MULLENS.
